CLAIM

The ornamental design for a hose connector component, as shown and described.

DESCRIPTION

FIG. 1 is a perspective view of a first embodiment of a hose connector component;

FIG. 2 is a front view thereof;

FIG. 3 is a rear view thereof;

FIG. 4 is a side view thereof (as taken from the left side of the hose connector component in FIG. 2);

FIG. 5 is a side view thereof (as taken from the right side of the hose connector component in FIG. 2);

FIG. 6 is a top view thereof;

FIG. 7 is a bottom view thereof;

FIG. 8 is a perspective view of a second embodiment of a hose connector component;

FIG. 9 is a front view thereof;

FIG. 10 is a rear view thereof;

FIG. 11 is a side view thereof (as taken from the left side of the hose connector component in FIG. 9);

FIG. 12 is a side view thereof (as taken from the right side of the hose connector component in FIG. 9);

FIG. 13 is a top view thereof;

FIG. 14 is a bottom view thereof;

FIG. 15 is a perspective view of a third embodiment of a hose connector component;

FIG. 16 is a front view thereof;

FIG. 17 is a rear view thereof;

FIG. 18 is a side view thereof (as taken from the left side of the hose connector component in FIG. 16);

FIG. 19 is a side view thereof (as taken from the right side of the hose connector component in FIG. 16);

FIG. 20 is a top view thereof;

FIG. 21 is a bottom view thereof;

FIG. 22 is a perspective view of a fourth embodiment of a hose connector component;

FIG. 23 is a front view thereof;

FIG. 24 is a rear view thereof;

FIG. 25 is a side view thereof (as taken from the left side of the hose connector component in FIG. 23);

FIG. 26 is a side view thereof (as taken from the right side of the hose connector component in FIG. 23);

FIG. 27 is a top view thereof;

FIG. 28 is a bottom view thereof;

FIG. 29 is a perspective view of a fifth embodiment of a hose connector component;

FIG. 30 is a front view thereof;

FIG. 31 is a rear view thereof;

FIG. 32 is a side view thereof (as taken from the left side of the hose connector component in FIG. 30);

FIG. 33 is a side view thereof (as taken from the right side of the hose connector component in FIG. 30);

FIG. 34 is a top view thereof;

FIG. 35 is a bottom view thereof;

FIG. 36 is a perspective view of a sixth embodiment of a hose connector component;

FIG. 37 is a front view thereof;

FIG. 38 is a rear view thereof;

FIG. 39 is a side view thereof (as taken from the left side of the hose connector component in FIG. 37);

FIG. 40 is a side view thereof (as taken from the right side of the hose connector component in FIG. 37);

FIG. 41 is a top view thereof; and,

FIG. 42 is a bottom view thereof.
